US0D1013638S

(12) **United States Design Patent** (10) **Patent No.:** **US D1,013,638 S**
(45) **Date of Patent:** **** Feb. 6, 2024**

(54) **OPTICAL FIBER CONNECTOR**

(71) Applicant: **A.J.WORLD CO., LTD.**, Seoul (KR)

(72) Inventor: **Sun Ho Choi**, Seoul (KR)

(**) Term: **15 Years**

(21) Appl. No.: **35/514,382**

(22) Filed: **Nov. 24, 2021**

(80) **Hague Agreement Data**

Int. Filing Date: **Nov. 24, 2021**

Int. Reg. No.: **DM/218559**

Int. Reg. Date: **Nov. 24, 2021**

Int. Reg. Pub. Date: **May 27, 2022**

(30) **Foreign Application Priority Data**

Aug. 27, 2021 (KR) 30-2021-0040756

(51) **LOC (14) Cl.** **13-03**

(52) **U.S. Cl.**

USPC **D13/133**
